[57] **CLAIM**

The ornamental design for a portable stereo television,
as shown and described.

DESCRIPTION

FIG. 1 is a front elevational view of a portable stereo television showing my new design;

FIG. 2 is a right side elevational view thereof, the left side being a mirror image;

FIG. 3 is a top plan view thereof;

FIG. 4 is a rear elevational view thereof;

FIG. 5 is a bottom plan view thereof;

FIG. 6 is a top, front and right side perspective view thereof; and,

FIG. 7 is a bottom, rear and left side perspective view thereof.

The middle portion of the power cord has been removed in FIGS. 2, 4, 5 and 7 for ease of illustration.
